UNITED STATES PATENT OFFICE.

GEORGE B. LEWIS, OF SAN FRANCISCO, CALIFORNIA, ASSIGNOR TO SHREVE & CO., OF SAN FRANCISCO, CALIFORNIA, A CORPORATION OF CALIFORNIA.

DESIGN FOR A BORDER-SECTION FOR PLATES, TRAYS, OR SIMILAR ARTICLES.

41,892.

Specification for Design.

Patented Nov. 7, 1911.

Application filed February 28, 1911. Serial No. 611,538. Term of patent 7 years.

To all whom it may concern:

Be it known that I, GEORGE B. LEWIS, a citizen of the United States, residing in the city and county of San Francisco and State of California, have invented a new, original, and ornamental Design for a Border-Section for Plates, Trays, or Similar Articles, of which the following is a specification, reference being had to the accompanying drawing, forming part thereof.

The figure is a plan view of a border sec-

tion for plates, trays, or similar articles, showing my new design.

I claim:

The ornamental design for a border section for plates, trays, or similar articles, as shown.

GEORGE B. LEWIS.
